DOOR

John A. Souza, San Jose, Calif.

Application October 5, 1937, Serial No. 167,406

3. Claims.

(Cl. 20—36)

The present invention relates particularly to house doors, and more particularly to the type of door opening upon the exterior of the building.

While most of these outer doors are either glazed or screened, it has become somewhat common practice to combine the two features in the one door. This is ordinarily accomplished by providing a pocket in the door into which the glazed sash may be dropped.

10 In order to provide a pocket of suitable size to receive a glazed sash it is necessary to increase the thickness of the door beyond that ordinarily required, and to so change the construction of the door as to materially increase the cost of production and at the same time materially reduce its strength and shorten the period of its useful life.

It is, therefore, the object of the present invention to provide a sash, either glazed or screened, associated with a door window in such a manner that it may be readily applied to a door of standard construction without weakening the same or in any way lessening its normal strength and rigidity.

25 It is another object to provide a door of the character indicated having either a screened or open window and an adjustable glazed sash operative from, and upon, the inside of the door.

It is also an object of the invention to provide a structure of the character indicated that will provide a simple, strong, durable and highly efficient means for adjustably positioning a glazed sash relative to a door window opening.

In the drawing:

35 Figure 1 is an isometric perspective drawing of a structure embodying my invention, partly in section and having parts broken away.

Figure 2 is a sectional view on line 2-2 of Figure 1.

40 Figure 3 is a side elevation of one of the sash supporting brackets and a portion of the rod upon which it is mounted.

Figure 4 is a sectional view through the door taken on line 4-4 on Figure 1.

45 In the particular embodiment of the invention herein disclosed, I show at 1 a portion of a door having a window opening 2 formed therein, the opening being provided with a shoulder 3 to receive the glazed sash indicated at 4.

50 At 5 is shown a guide rod mounted upon the upper portion of the door above the opening 2 as at 6, and having its lower end slidably seated in a step or foot bracket 7 on door 1. This rod 5 has a gooseneck formation at its upper end as indicated at 8 to accommodate a shade roller.

curtain rod, or similar device. Between the part 8 and the bottom end of the rod, it extends in spaced and parallel relation to the door as at 9, with a part 10 opposite the upper end of the opening curving inwardly into closer relationship with the door as indicated at 11.

The rod 5 is additionally supported in fixed and rigid relation to the door 1 by means of brackets as 12. These brackets are rigidly mounted on the door as at 13 and extend outwardly therefrom as at 14 and thence at right angles to the rod as at 15. While but one such bracket is shown in the drawing as many as may be deemed necessary may be applied.

At 16 is shown a shoe mounted to slide freely on rod 5 and provided with a slot at 17 to permit it to pass any bracket 12 that may be placed in its path of travel. To hold the shoe at all times in such a position that the slot 17 is aligned with the bracket 12, I provide a guideway as 18 in rod 5, and an engaging pin or spline 26 in shoe 16.

On the shoe 16 is mounted a spring member 19 having a forked end 20 to engage a button 21 on the sash 4. This spring member 19 is so formed that it will readily pass within any bracket 12 that it may encounter, and of such tension that when in the position on rod 1 shown in Figure 1 it will seat the sash firmly in the window opening, but when the shoe is moved outwardly on the rod when the sash is lowered the spring will 30 carry the sash outwardly with it. The button 21 is mounted on the top stile of the sash, and the parts 16 to 21 are associated in such a manner as to cooperate in properly positioning the top portion of the sash.

On the lower portion of the sash 4 is mounted a button 22 which is engaged by the forked end 23 of another spring member 24. This spring member 24 is also so formed that it will pass readily within any bracket 12 that it may encounter, and is mounted upon a shoe 25 which slides easily on rod 5. This shoe 25 is also provided with a spline 26 to engage guide 18 to hold it at all times in a proper position relative to the bracket 12, and the spring member 24 is so designed that it at all times exerts an outward pressure on the lower portion of sash 4. 40 45

For supporting the sash at any desired height I provide a bracket as 27 on shoe 25 upon which is pivotally mounted a dog 28. One end of the 50 dog 28 is positioned to engage any one of the notches 29 in rod 5, and the other end parallels the part 30 of the bracket 27, from which it is separated by a rubber block 31 operative to urge the dog into engagement with a notch.

In assembling the structure the two shoes and the parts carried thereby are mounted on the rod 5 before the foot bracket 7 is placed in position, and then they are placed in engagement with the buttons 21—22 on sash 4, resiliently supporting the sash in place as shown.

To remove the sash 4 it is only necessary to pull the bottom out by means of the knob 32 against the pressure of the spring element 24. By releasing the dog 28 from engagement with a notch 29 the sash may be drawn downwardly. As the sash slides down the shoe 16 moves down off of the cam portion 11 and carries the upper portion of the sash outwardly and free of the door. Since the bottom of the sash is pulled out by hand the sash may be drawn down to uncover the whole window opening without danger of contact with the surface of the door and consequently without danger of injuring the same.

By releasing the dog 28 at any desired point the sash may be positioned as desired to uncover any portion of the window opening. If so desired the buttons 21—22 may be made to rotate to permit disengagement from the spring members, whereby the sash may be removed completely from the door.

It is to be understood, of course, that while I have herein shown and described but one specific example of the invention, changes in form, construction, and method of assembly and operation may be made within the scope of the appended claims.

I claim:

1. Means for adjustably supporting a sash in a door window opening comprising, a pair of guide rods fixedly mounted on opposite sides of the opening and in spaced parallel relation to the door, shoes slidably mounted on the rods, and resilient members inserted between the sash and shoes to urge the sash into the window opening.

2. In combination, a door having an opening formed therein provided with a seat for a sash, a sash insertable in said opening to bear against said seat, a pair of guide members fixedly mounted on opposite sides of the opening and in spaced parallel relation to the door with portions adjacent the upper end of the opening turned inwardly into closer relationship with the door, shoes slidably mounted on said guide members, and members resiliently supporting the sash on the shoes to urge the sash into the window opening and against the seat, the uppermost shoes being disposed to engage the inwardly turned portions of the supporting members when the sash is seated in the window opening.

3. In a door having an opening therein and a sash removably mounted in the opening, a supporting device for the sash including a supporting rod mounted on the door, a shoe slidably mounted on the rod, a spring member mounted on the shoe on one end and having its other end slotted, and overlying the sash, a slot engaging device on the sash, and a catch inserted between the shoe and rod.

JOHN A. SOUZA.
